UNITED STATES PATENT OFFICE.

RICHARD M. ROCKEY, OF NORA, ILLINOIS.

COMBINED MILK-COOLER AND REFRIGERATOR.

SPECIFICATION forming part of Letters Patent No. 299,166, dated May 27, 1884.

Application filed March 12, 1884. (No model.)

To all whom it may concern:

Be it known that I, RICHARD M. ROCKEY, a citizen of the United States, residing at Nora, in the county of Jo Daviess and State of Illinois, have invented a new and useful Combined Milk-Cooler and Refrigerator, of which the following is a specification, reference being had to the accompanying drawings.

My invention relates to a combined refrigerator and milk-cooler; and it has for its object to provide a device of this character which shall be cheap and simple in its construction, and effective in use for cooling milk and preserving perishable articles.

With these ends in view, the invention consists in the improved construction and combinations of parts hereinafter fully described, and pointed out in the claims.

In the drawings, Figure 1 is a perspective view of my invention, the doors being opened for the reception of the milk-cans and other articles. Fig. 2 is a transverse section, and Fig. 3 is a longitudinal section.

In the accompanying drawings, in which like letters refer to corresponding parts in the figures, A represents a box or casing constructed, preferably, of wood, and made substantially rectangular in form. This box or casing A may be provided at any suitable point upon its sides or ends with a door, B, and is provided with a hinged cover, C, having strips a.

D represents an inner casing, which is constructed of thin sheet metal, the upper edges being bent at an angle upon the top edges of the casing A, and secured thereon by strips b. This metal casing D is so arranged as to leave a space, c, between itself and the casing A, to allow of the free circulation of air, and to keep the inner casing from contact with the outer air, thus rendering it much easier to cool and keep cool the same. The side of the casing D, at the point where the door B is located, is provided with an opening, d, to the sides of which is secured a sheet-metal box or casing, C', the front end of which is opened, so that access may be had to the same by means of the door B, the casing being situated so that its body portion is entirely within the casing D.

To the under side of the hinged cover C is provided a sheet-metal lining, e, which is

creased or formed with longitudinal depressions or grooves f, which register with openings g, formed in the sides of the strips a, in order that the air may freely circulate above the cans which are to be placed within the casing D, thus carrying off any odors that may arise from the milk.

E represents an inlet tube or pipe, which is arranged upon the upper end side of the casing, and through which water may be introduced from a hydrant or pump by means of a pipe.

F represents the outlet-pipe, which is arranged upon the lower end side of the casing opposite the inlet-tube, and communicating with any suitable waste-pipe.

In the application of my improvement the water-tight cans for containing the milk are placed within the casing D, and the water fed directly thereto through the inlet-pipe. In using the same for the preservation of vegetables, meats, &c., the same are placed within the box C', and as this box is within the casing D, are subjected to the cooling action of the water. It will therefore be seen that my improvement is applicable for cooling milk, and preserving perishable articles of food, and that its construction is simple and durable.

Having fully described my invention, what I claim as new, and desire to secure by Letters Patent, is—

1. In a combined milk-cooler and refrigerator, the combination, with an outer box or casing, of an inner casing constructed of thin sheet metal, and arranged within the outer casing to form an air-space, and a box or casing arranged upon the inner side of the inner casing, access being had thereto by means of an opening in the side of said casing, and a door for closing the same, substantially as set forth.

2. In a combined milk-cooler and refrigerator, the combination, with an outer and an inner casing, of a hinged cover having a lining of sheet metal provided with longitudinal grooves or recesses, and openings in the sides of the cover communicating therewith, substantially as and for the purpose set forth.

3. In a combined milk-cooler and refrigerator, the combination of an outer and an inner casing, a box or casing secured therein,

an opening in the side of the inner casing, a
door communicating with said box, inlet and
outlet tubes suitably arranged, and a hinged
cover having a lining of sheet metal provided
5 with longitudinal grooves, the sides of the
cover having openings registering with said
grooves, substantially as set forth.

In testimony that I claim the foregoing as
my own I have hereto affixed my signature in
presence of two witnesses.

RICHARD M. ROCKEY.
